UNITED STATES PATENT OFFICE.

CARL PETERS, OF CREFELD, GERMANY.

BOOT OR SHOE.

SPECIFICATION forming part of Letters Patent No. 691,291, dated January 14, 1902.

Application filed March 7, 1900. Serial No. 7,694. (No model.)

To all whom it may concern:

Be it known that I, CARL PETERS, a subject of the King of Prussia, German Emperor, and a resident of Crefeld, in the Kingdom of 5 Prussia and German Empire, have invented certain new and useful Improvements in or Connected with Boots, Shoes, or the Like, (for which I have applied for patents in England, dated January 30, 1900; in France, dated 10 January 30, 1900; in Belgium, dated January 29, 1900, and in Germany, dated September 23, 1899,) of which the following is a specification.

This invention is an improved boot or shoe 15 fastener which may be operated in a satisfactory manner merely by the insertion or withdrawal of the foot itself without the assistance of contracting bands, springs, or the like. This peculiar novel mode of working 20 is attained by the improved construction of the fore part of the boot-upper, which within certain limits is independent of the rear part of the upper, or vice versa. The rear part of the boot-upper may be movable independently 25 of the front part of the upper, the movable part being provided with a strap or loop which extends into the boot in such a way that the foot will catch and press the loop down when the boot is put on, causing the movable piece 30 of the upper to close upon the foot. To facilitate closing the movable piece and to prevent the entrance of dust and moisture at the point of overlapping of the former, a tongue-piece may be inserted between the 35 fixed and movable parts.

My invention enables the boots or shoes to be put on or taken off with very great facility and rapidity and also insures a perfect fit of the boot on the foot. When walking, the 40 strap or loop connected with the movable piece lifts a little and relieves the pressure on the instep or front of the foot which is found so unpleasant particularly in long walks.

In the accompanying drawings, Figure 1 45 represents a longitudinal section of a shoe ready for use. Fig. 2 is a side view thereof. Fig. 3 is a rear view; and Fig. 4, a similar view, partly in section.

a indicates the movable front part of the 50 upper of the boot, and *b* the rear part of the upper. Both parts are connected by a foldable flap or tongue *c*. The two side flaps *a'* of the fore part of the upper *a* will bend on the line *d* in order to allow of their being

55 moved forward, and their ends are connected by a strap or a band *e*, which passes through the interior of the boot or shoe, entering the latter through slits *f*. As shown, this strap is attached to a thin leather disk *g*, fitted to the shape of the heel, and fits as closely as 60 possible to the walls of the heel part of the interior of the boot or shoe. To prevent disk *g* turning over, a loose extension of the pulling-strip *h* may be fastened to the movable disk *g*, as shown in Fig. 1. In order to keep 65 the flaps *a'* properly stretched longitudinally, elastic steel bands *n* may be attached thereto, as shown.

When the boot is to be drawn on, the front part or the instep of the foot entering the inside of the shoe pushes the fore part of the upper *a* forward, simultaneously raising the strap *e* and the plate or disk *g*, so that the boot assumes the form shown in Fig. 1, in which the tongues *c* are extended, the foot 75 thus entering without resistance into the extended mouth or opening of the boot until the heel encounters the plate *g* and exerts a pressure downward thereon in the direction indicated by the arrow in the drawings, whereby the strap *e* is drawn taut and the flaps *a'* 80 of the upper *a* are closed. (See Fig. 2.)

The arrangement hereinbefore described is of course applicable for any kind of boots, not only high uppers, but also half-shoes and 85 the like.

What I claim as new is—

1. In a boot or shoe, the combination of the opposite flaps *a'*, the internally-movable plate *g*, the straps *e* passing through openings in 90 the side of the shoe and connecting said plate with these flaps; with a tongue *c* interposed between the flaps and the rear part of the shoe, and the pulling-strap *h* connected to the plate *g*. 95

2. In a self-closing boot or shoe, the combination of the opposite flaps *a*, the internally-movable plate *g*, the straps *e* passing through openings in the side of the shoe and connecting said plate with these flaps; with the pulling-strap *h* connected to the plate *g*. 100

In testimony whereof I have hereunto set my hand in the presence of two witnesses.

CARL PETERS.
